PORTABLE GRILL

Joseph B. Forrest, Charlotte, N. C.

Application September 12, 1955, Serial No. 37,881

Term of patent 14 years

(Cl. D81—10)

Figure 1 is a top perspective view of a portable grill embodying my new design with the two sections in position for cooking;

Figure 2 is a top perspective view thereof, with the two sections in closed position; and

I claim:

The ornamental design for a portable grill, substantially as shown.
